UNITED STATES PATENT OFFICE.

GUSTAVE E. VILLARET, OF LEONIA, NEW JERSEY, ASSIGNOR TO MARKEL ELECTRIC PRODUCTS, INC., OF BUFFALO, NEW YORK, A CORPORATION OF NEW YORK.

DESIGN FOR A GRILLE FOR LOUD SPEAKERS.

Application filed November 23, 1928. Serial No. 29,005. Term of patent 3½ years.

To all whom it may concern:

Be it known that I, GUSTAVE E. VILLARET, a citizen of the United States, residing at Leonia, in the county of Bergen and State of New Jersey, have invented a new, original, and ornamental Design for Grille for Loud Speakers, of which the following is a specification, reference being had to the accompanying drawing, forming part thereof.

In said drawing:

Figure 1 is a part elevation of a grille for loud speakers embodying my new design. In this figure half of the design is shown in full lines and the remaining half in outline in dot and dash lines, the pattern being repeated.

Figure 2 is a side elevation of the same.

I claim:

The ornamental design for a grille for loud speakers, substantially as shown.

GUSTAVE E. VILLARET.
